TUYÈRE BLOCK

Rudolph G. Felger, Alex C. McLellan, Arthur S. Griswold, and Ernest E. Dubry, Detroit, Mich.

Application October 11, 1934, Serial No. 747,842

13 Claims. (Cl. 110—44)

The present invention relates to tuyères used to supply air from an air passage to a bed of fuel used for heating boilers or the like, and particularly to tuyères used in boilers or the like wherein the fuel is fed to the combustion chamber by mechanical fuel feeding means, such as automatic stokers or the like.

Tuyère blocks heretofore used have had a relatively short life due to burning of the block by the heat of combustion of the fuel. Such blocks become less efficient for supplying air to the fuel in the combustion chamber as they deteriorate due to such burning, until it is necessary to draw the fires, cool the combustion chamber and replace the burned blocks. It also has been observed that serious fires in the air supply ducts frequently were due to burning embers dropping through the tuyères which had become defective by reason of heat which had burned through a portion of the shell of the block. Some prior attempts sought to overcome these difficulties by cooling the nose of the tuyère block with baffled air currents passing through the block and thereafter discharging the air substantially horizontally of the block. Such structures caused excessive turbulence in the air stream and have a much shorter life and lower efficiency than the block of our present invention.

It is an object of the present invention to provide a tuyère block which is so constructed that the air streams passing through the block are utilized to cool the nose portion of the block and are thereafter introduced, through relatively unrestricted air passages with the minimum of turbulence, into the combustion chamber.

It is a further object of the present invention to provide a tuyère block in which excess metal at the nose portion has been removed and its construction is such that the air passing through the interior thereof is effective to cause a substantial cooling of the block.

It is a further object of the present invention to provide a tuyère block having a depending rib in the interior thereof which is effective to conduct the heat from the surface of the block to the interior of the block and to transfer the heat to the air streams passing therethrough. The said rib is effective also to direct the air blast outwardly from the interior of the block, forwardly of the nose portion thereof and toward the thicker portions of the fuel bed.

It is a further object of the present invention to provide a tuyère block which is relatively simple to construct, economical to operate and which has a relatively long life of service, being so con-

structed that a substantially unimpeded body of air circulates through the block and is thereafter discharged directly into the body of the fuel to be burned.

Other objects of this invention will appear in the following description and appended claims, reference being had to the accompanying drawings forming a part of this specification wherein like reference characters designate corresponding parts in the several views.

Fig. 1 is a fragmentary view, partly in side elevation and partly in vertical section, showing a combustion chamber equipped with a series of tuyères constructed in accordance with the present invention.

Fig. 2 is a view in perspective of one of the tuyère blocks embodying the present invention.

Fig. 3 is a top plan view of the tuyère block shown in Fig. 2.

Fig. 4 is an enlarged fragmentary view in side elevation of a tuyère block shown in the solid line view, fragmentary views of the tuyère blocks directly adjacent thereto being shown in the broken line.

Fig. 5 is a sectional view taken substantially on the line 5—5 of Fig. 4 in the direction of the arrows.

Fig. 6 is a sectional view taken substantially on the line 6—6 of Fig. 4 in the direction of the arrows.

The terms "front", "forward", and terms of similar meaning when applied to the tuyère of the present invention refer to those portions of the tuyère which face the center of the combustion chamber.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring to Fig. 1, tuyère blocks of the present invention each consists of a body portion 10 having a stepped nose portion 11 and an inclined heel portion 12. As shown in Fig. 1, a plurality of separate tuyère blocks of the present invention are supported on an inclined tuyère block supporting base 13 by means of bolts (not shown) which extend through holes passing through lugs 55

14 and 15 (Fig. 5) formed on opposite interior sides of the walls. Rows of tuyère blocks are placed in the combustion chamber in tiers or layers on each side of the fuel passage or valleys 5 16 and communicate with the air ring or collar (not shown) through which air under predetermined substantially constant pressures (which may be varied in accordance with the amount of fuel to be burned) is supplied to the combustion 10 chamber of the furnace or boiler. The tuyère block constructed in accordance with our present invention is provided with a plurality of ports or nozzles 17 adjacent each stepped surface of the nose portion 11, each port 17 communicating with 15 an air passage 18 which is defined by the interior of the sides of the body 10, and a depending rib 19. In contravention to the customary practice in the art, the nose portion of the tuyère block of the present invention is recessed as at 20 to provide a pocket in which the ash or other solid 20 products of combustion will be retained to thereby form an insulating blanket at the point where the tuyère block is subjected to the greatest amount of heat, and the ports 17 discharge air 25 streams which travel forwardly and outwardly at an angle to the center line of the tuyère on each side of the nose portion 11.

The stepped nose portion 11 is provided with a plurality of flat substantially horizontal fuel 30 supporting surfaces or tables 21. Each table 21 has an exposed surface 21a and a rearwardly extending portion 21b located beneath the forward overhanging fuel supporting surface 21a of the next higher step of the block. This construction 35 is such that if the nose portion or any part of the exposed table section 21a of any one of the successive steps of the block should burn through, burning embers, ash or other material from the interior of the combustion chamber 40 would drop through the burned-out portion and be caught on the supporting surface 21b of the table section directly beneath. Such material would tend to be blown back into the fuel bed by the air blast. In this manner the tuyère 45 block of the present invention prevents foreign matter, such as burning embers, ash, or the like, from falling downwardly through the tuyères and into the air collar or chamber. We have found that this construction prevents many fires 50 in the air chamber which occur in the use of tuyères of conventional design with consequent damage resulting to the air control mechanism.

The tuyères block of the present invention may be adapted to any particular type of combustion chamber design, one type of which is shown in the present drawings and comprises the tuyère block supports 13 which also act as the air blocks forming the connecting passageway between the tuyère blocks and the air collar. In this construction the heel portion 12 of the tuyère block is preferably provided with a rabbeted portion 22 which engages with a ledge on the air block and thus provides an effective seal which prevents leakage of air between the 65 heel 12 of the tuyère and the tuyère support 13. The extended flat surfaces provided on the bottom and top portions of each tuyère block are so arranged that when the blocks are placed in superimposed relation, the flat bottom surface of 70 the top block cooperates with the flat top surface of the adjacent bottom block to effect an air seal which prevents any substantial leakage of air from between the adjacent blocks.

The interior construction of each of the separate steps or tiers of the tuyère block is shown in

Fig. 5. It will be there observed that the recessed portion 20 of the nose 11 is formed in direct integral connection with the rib 19 which extends rearwardly therefrom to the interior of the tuyère block. The rib 19 thus extends throughout the length of the inclined nose of the tuyère block and depends inwardly into the air chamber. The air passing from the air collar through the tuyère supporting air block impinges against the rib 19 and is divided into two streams which are directed forwardly and outwardly through the air passages 18. The axes of these passageways 18 preferably are curved outwardly at an angle of less than 90° to the center line of the tuyère block in such a manner that the air blast is directed into the sides of the stream of fuel at points forwardly of the tuyère nose. (In a preferred form of the invention as here shown the center line of each of the passageways 18 extends outwardly at an angle of substantially 51° to the center line of the tuyère.)

In a typical installation of tuyère blocks embodying the present invention the blocks are placed in superimposed relation to form a series of spaced tiers extending about the combustion chamber. These tiers are spaced a distance apart, preferably from twelve to eighteen inches. With this spacing of the tiers of the tuyères having the air streams discharged outwardly at an angle of approximately 51° to the center line of the tuyère, it has been found that the air streams from opposed tiers of tuyères intersect and converge in the spaces between the tiers of tuyères and forwardly of the noses thereof. These points of intersection and convergence of the air stream lie substantially in a plane which extends above and substantially parallel to the inclined plane of the nose portions of the tiers of tuyères. The angle of inclination of such planes will be found to vary for particular installations but by arranging the spaces between the tiers in accordance with the angle of inclination of the tiers and the angular direction imparted to the air stream by the air ducts, it will be found that a construction embodying the present invention will effect maximum burning of the fuel at points removed from the nose portion of the tiers.

It is known that fuel tends to burn at the greatest temperature at the point of maximum air supply. In order that this maximum temperature shall not be generated either at or below the plane of the nose of the tuyères, the present invention provides a construction wherein the maximum air supply is discharged into the fuel bed at points forwardly of the nose portions of the tuyères and above the plane thereof so that the maximum temperature resulting from the combustion of the fuel occurs at a distance from the nose portions of the tuyères. Such construction also has been found to prevent any substantial burning of the fuel in the spaces between the tiers of the tuyères or substantially in the plane of the tuyère noses.

The provision of the recessed portion 20 in the nose portion 11 of each step of the tuyère block permits the elimination of surplus material in the nose portion which, if provided in an excess amount, results in the accumulation of excess heat at such points and a consequent burning of the metal. In the construction herein provided the amount of metal is such that the heat passing into the nose portion of the tuyère block is rapidly conducted into the rib 19 and radiated through

the rib 19 to the air passing through the air passages 18. At no time is there any substantial accumulation of heat in the nose portion of the tuyère. The provision of the rib 19 thus not only effects the cooling of the nose 11 of the tuyère block by carrying away the heat therefrom and dissipating it into the air stream, but also acts as a means for increasing the preheating of the air prior to combustion as it passes through the passages 18 and the ports 17. This construction, because of the heating of the air in the substantially unrestricted air passages, increases its velocity during the passage therethrough just prior to discharge through the ports 17. It has been found that this tends to lessen the load on the air supply fan and secures a substantially greater penetration of the air into the fuel bed than with other proposed constructions.

It will be observed that this construction is such as to give substantially unimpeded air passages which permit the flow of air from the air collar directly into the combustion chamber with a minimum of turbulence and without reversing the direction of the air stream. The construction also imparts positive direction to the air streams into the body of fuel at a point forwardly of the tuyère. Difficulties heretofore have been experienced with tuyère blocks of conventional construction due to the fact that the air passing through the tuyère block was baffled in such a manner as to create considerable turbulence within the block and creating substantial back pressure on the air supply fan. Such construction also prevented a positive directing of the air streams into the fuel bed at a predetermined point in advance of the tuyère. In a tuyère of the construction herein disclosed, the predetermined point at which the air is discharged into the fuel is a point removed from the tuyères where the fuel bed is relatively thick. It has been found that the fuel bed will vary in depth due to load conditions from a few inches to as high in some cases as two or three feet. The bed at substantially all times is ordinarily thicker at certain regions laterally of or more remote from the tuyère, so that by virtue of the present invention a tuyère construction is provided which causes the air streams to be discharged into the portions of the fuel bed having the greatest depth and as a consequence requiring the greatest penetration of the incoming air blast.

In testing the tuyère block of the present invention, it has been found that as compared with a tuyère block of standard construction, the number of tuyère blocks replaced per thousand tons of fuel burned has been reduced from 3.2 to 0 over a period during which 32,000 tons of fuel were burned. Thus the present tuyère block will permit continuous operation of the boiler for a greater period of time than the tuyère blocks of conventional design.

It also has been found that tuyère blocks embodying the present invention show less tendency to warp than tuyère blocks of conventional design. This is largely due to the plurality of stepped ledges 21 and the reinforcing ribs 19.

While the present invention has been shown in a preferred embodiment in which a plurality of substantially horizontal fuel supporting surfaces are placed at the nose 11 in stepped relation to each other, it is to be understood that the number of ledges and the number of air ports which may be placed on any one of such blocks may be varied to conform to various operating conditions.

Thus, in contravention to the usual practice of

providing single-step tuyère blocks of box-like shape, our invention contemplates, when considered from one of its broader aspects, providing a novel tuyère block consisting of a plurality of forwardly diverging curvilinear nozzles, the walls of which are mutually merging to provide the outside walls of the block and the rearwardly extending cooling rib, said block having surfaces which must be exposed to the action of the radiant heat reduced to a minimum and adapted to accumulate protective layers of ashes and to keep said layers without permitting the air from the ports or from leaking seams to blow them away, or to promote burning of the fuel in close proximity to the block. Considered from another of its broader aspects, the present invention contemplates providing a novel tuyère block in which the total amount of heat imparted to the mass of the block per unit of time by radiation and conduction, balances the amount of heat given up by said block to the air moving therethrough, at a sufficiently low temperature, that is, at a temperature at which no rapid burning out of the metal results.

Tuyère blocks of the present invention may be used with various types of stoker installations in the combustion chambers of boilers or furnaces and the present description, therefore, has been directed more particularly to the tuyère unit itself, the particular types of stoker constructions being well known to those skilled in the art.

We claim:

1. A tuyère block having a plurality of stepped substantially flat fuel supporting surfaces, an air passage extending through the interior thereof and having discharge nozzles beneath the fuel supporting portions and arranged to discharge air horizontally into the body of fuel forwardly and laterally of the tuyère block, each of said stepped substantially flat surfaces having a nose portion recessed to provide a valley therein, a reinforcing rib extending from said valley and into said air passage and having a formed surface adapted to deflect air outwardly through said nozzles at an angle, less than 90°, to the center line of the tuyère.

2. A tuyère block having interior walls and a portion forming a substantially horizontal fuel supporting surface, a recessed multiple-step nose portion formed adjacent the forward edge thereof, a reinforcing rib depending downwardly therefrom and extending longitudinally thereof and forming with said interior walls of the block a plurality of air nozzles terminating at one end in ports adjacent the opposite edges of said fuel supporting portion.

3. A tuyère comprising in combination a hollow shell having a forwardly extending recessed multiple-step nose portion and curvilinear nozzles extending through said shell on opposite sides of said nose portion and adapted to discharge streams of air into a fuel bed at points forwardly of said recessed nose portion and at an angle to the median line thereof.

4. A tuyère comprising in combination a hollow shell having a rearwardly and centrally recessed nose portion of multiple-step construction and centrally partitioned nozzles extending through said shell on opposite sides of said nose portion and adapted to discharge streams of air into a fuel bed at points forwardly of said recessed nose portion and at an angle outwardly to the median line thereof.

5. A tuyère comprising in combination a hollow shell having a forwardly extending recessed nose portion of multiple-step construction, a de-

pendent rib of heat conducting material extending downwardly into said hollow shell on a line substantially co-extensive with the longitudinal median line of said nose portion, and nozzles extending through said shell on opposite sides of said depending rib, the inner walls of said nozzles merging smoothly into said rib, and said nozzles being adapted to discharge streams of air into a fuel bed forwardly of said recessed nose portion 10 and at an angle outwardly to the center line of said nose portion.

6. A tuyère comprising a series of horizontal vertically spaced table sections receding upwardly in stepped relation and each terminating in 15 a centrally recessed nose portion, a central partition dividing the space between each adjacent pair of table sections into a pair of forwardly diverging air nozzles terminating in ports, said partitions being extended rearwardly to provide 20 a common substantially continuous dividing wall longitudinally of the tuyère.

7. A tuyère comprising a series of horizontal vertically spaced table sections receding upwardly in stepped relation and terminating in a centrally recessed nose portion of multiple-step 25 construction, a central partition dividing the space between each adjacent pair of table sections into a pair of forwardly diverging air passages terminating in nozzles, said partitions being extended rearwardly to provide a single continuous dividing wall longitudinally of the tuyère and the mouth of each nozzle extending at least 30 in part in advance of the base of the adjacent recessed portion.

35. 8. The combination in a combustion chamber of a source of air supply, a series of unitary tuyère blocks arranged in spaced substantially parallel inclined tiers within said combustion chamber and communicating with said source of air supply, each of the tuyère blocks having an indented nose portion of multiple-step construction, and air supply ducts discharging on opposed sides thereof and so arranged in said tiers that the tips of said indented nose portions lie substantially in a common inclined plane and the air streams from the opposed faces of the separate tiers of the tuyères intersect and converge in a plane lying above and substantially parallel to the inclined plane of the nose portions thereof.

50. 9. A unitary tuyère block including a plurality of integrally formed air nozzles, said nozzles having curvilinear air passages adapted to discharge air forwardly and laterally at both sides of the block, said nozzles being arranged in pairs, one pair above and rearward of the other, the nozzles in each individual pair being divergently disposed with relation to each other and forming in front of the block a forwardly extending shelf portion adapted to accumulate in operation a protective layer of ashes.

65. 10. A unitary tuyère block comprising a plurality of integrally connected air nozzles, said nozzles forming curvilinear air passages adapted to discharge air forwardly and laterally at both sides of the block, said nozzles being arranged

in pairs, one pair above and rearward of the other, the nozzles in each individual pair being divergently disposed with respect to the vertical plane passed through the median line of the block, the outer side walls of the nozzles merging smoothly, one into another, to form the side walls of the block, the inner side walls of said nozzles similarly merging to form a rib extending rearwardly within the interior of said block along said vertical plane.

11. A unitary tuyère block comprising a plurality of integrally connected air nozzles, said nozzles forming curvilinear air passages adapted to discharge air forwardly and laterally at both sides of the block, said nozzles being arranged in 15 pairs, one pair above and rearward of the other, the nozzles in each individual pair being divergently disposed with respect to the vertical plane passed through the median line of the block, the outer side walls of the nozzles merging smoothly 20 one into another to form the side walls of the block, the inner side walls of said nozzles similarly merging to form a rib extending rearwardly within the interior of said block along said vertical plane, and the horizontal bottom walls of 25 each pair of nozzles merging and extending forwardly between the nozzles of the pair to form an ash collecting shelf.

12. In combination, a pair of tuyère blocks superimposed in stepped relation, each block having a closed front wall of multiple-step construction extending centrally across the major portion of the forward face thereof, said blocks also having extended substantially plane contacting walls adapted to engage in a substantially 30 air-tight manner, whereby no air can emerge from the central portion of the front of either of said blocks nor from between said blocks near the central portion thereof, thus preventing burning of the fuel in close proximity of said 40 blocks as well as preventing blowing away of the protective ash layers.

13. In combination, a pair of tuyère blocks superposed in stepped relation, each tuyère having plane top, bottom and side walls and a front 45 wall including forwardly extending plane sections forming an angle with said side walls, said sections having apertures therein whereby to direct the air laterally and forwardly of said tuyère, said front wall also including a curvilinearly recessed portion connecting said sections, said blocks being superimposed with the plane sections of the front wall of the upper tuyère spaced rearwardly of the corresponding sections of said lower tuyère, the plane top of the lower 55 tuyère extending forwardly of the front of the upper tuyère to form air-swept and ash-receiving shelf portions, the plane top of the lower tuyère extending in surface engagement with the plane bottom of the upper tuyère and rearwardly to the full extent thereof, whereby to form an air-tight seal between said tuyères.
